DANIEL PRICE, OF LOCKPORT, NEW YORK.

Letters Patent No. 105,979, dated August 2, 1870.

IMPROVEMENT IN URINAL ATTACHMENT TO A BED.

The Schedule referred to in these Letters Patent and making part of the same.

To all whom it may concern:

Be it known that I, DANIEL PRICE, of Lockport, in the county of Niagara and State of New York, have invented a certain new and useful Improvement in "Urinors" for night use, of which the following is a specification.

Nature of the Invention.

This improvement is of that class where a tube extends down from the bed to a receiver beneath, for the accommodation of invalids and others who cannot well arise.

The invention consists in an improved form of the socket or "urinor," fitting the private members; also, in the covering of the same, and the method of attachment and connection to the bed and to the receiver.

General Description.

Figure 1 shows the arrangement applied to a bed, and adapted to the use of males.

Figure 2 shows an elevation of the same, adapted to the use of females.

C represents a flexible pipe or rubber, or other material, having at the outer end a tip or nozzle, f, which passes through a hole, d, in the cover e of the receiver D, which may be of earthenware, copper, or other material.

A packing-disk, e, of rubber, or equivalent, slides upon the tube, and fits down closely over the orifice in the cover, thereby preventing the escape of odor. This is one feature of improvement in my device.

A thimble or slide, E, also rests upon the pipe above the receiver.

This is provided with a clasp, P, or other device of a similar nature, which serves to attach the pipe to the rail of the bedstead, either inside or out, by means of a screw eye, q, or equivalent.

This is another feature of my improvement I claim, as thereby I not only provide a secure fastening, but the pipe C can be adjusted therein to any desired length or position.

From this point the tube C extends upward, and has at the top the socket or "urinor" B or B', according as it is intended for male or female use.

For the former, a simple tube of rubber or metal is employed; for the latter, the upper portion of the socket is enlarged to fit properly to the member.

This shape, as seen in fig. 2, I also claim as an improvement over any device heretofore known.

A cover, a, also of rubber or metal, and of the

proper form, is made to fit the mouth of the socket or "urinor," and over the whole fits a cloth cover or wrapper, b, which envelops the whole socket, being of similar shape, the top forming a flap which turns down and buttons in place.

I also claim a novelty in this covering or wrapper, as it shuts the whole in securely and prevents odor. It also absorbs moisture, and serves as a convenient hand-piece in handling.

These features above described I believe to be new, though I am aware that the pipe has before been used, as shown in the patents to Willing and Van Rensselaer, the latter dated March 17, 1868.

I disclaim the broad principle shown in these patents, and rest my claim only on the features of improvement I have specified.

This arrangement serves a very convenient purpose for invalids of all kinds and of both sexes, as it prevents the necessity of arising from bed.

The person has only to reach out between the ticks to take the "urinor" and apply it, which costs but little effort.

It avoids the necessity of arising, which is fatiguing and dangerous for invalids, and frequently destroys a night's rest, if no further difficulties follow.

It also prevents the foul odor which is common from the open standing of urine in the vessel, for the reason that, when not in use, the receiver is tight, and the "urinor" itself is covered by the wrapper b.

When not in use, the tube is to be removed and thoroughly cleaned and hung up to air.

In cases of extreme necessity, a thin flexible tube may be connected to the mouth of the "urinor," and the virile member, by any device necessary for the purpose.

I disclaim the broad principle of the use of a tube extending from the bed to a receptacle upon the floor; but

What I claim, and desire to secure by Letters Patent, is—

The packing-disk e, the thimble or slide E, with clasp p, or equivalent, the wrapper b, and the cover a, when arranged and operating in connection with the pipe C and "urinor" B or B', in the manner and for the purpose specified.

In witness whereof I have hereunto signed my name, in the presence of two subscribing witnesses.

DANIEL PRICE.
